COMBINATION ORGAN STOP ACTION

Filed May 20, 1932

UNITED STATES PATENT OFFICE

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT

COMBINATION ORGAN STOP ACTION

Application filed May 20, 1932. Serial No. 612,501.

This invention relates to organs of the type having traces by means of which various combinations of stops can be operated.

A pipe organ usually comprises a number of manual organs or sub-organs, such as the great, choir, and swell, and a pedal organ or sub-organ, and each sub-organ is provided with suitable stop actions by means of which the several registers of pipes can be opened or closed at will.

It is usual to provide organs with means by which the various combinations of stops can be readily and quickly made up and operated, and such means includes what is known in the art as "traces". Traces of this kind are shown in my earlier Patent No. 1,078,079, dated November 11, 1913. In some instances, the stop actions of the pedal organ are entirely independent of the combination stop actions of the manual so that, when a manual combination stop action is operated, the stop actions of the pedal organ are not affected or disturbed. Some organists prefer this arrangement. It has been proposed to provide organs wherein the pedal stop actions and the manual stop actions are associated in such manner as to be made up in various combinations, but in this arrangement, when a trace is operated through one of the manipulative devices associated with the manual, the stop actions of the pedal organ are disturbed. This arrangement is preferred by some organists, but others wish the pedal stop actions to be operated entirely independently of the manual stop actions, as in the first instance.

The aim of the present invention is to provide an improved arrangement by means of which the pedal stop actions may, at will, either be associated with the combination stop actions of the manual or may be entirely divorced from the manual stop actions, thus allowing for flexibility and selectiveness and meeting the requirements of all organists.

A further aim of the invention is to provide an improved organ mechanism having a trace mechanism provided with actuators associated with the manual stop actions,

and actuators associated with the pedal stop actions, the latter actuators being rendered effective and ineffective at will, and the mechanism being characterized by its extreme simplicity in construction, its compactness in arrangement, and the ease and facility with which it may be set up and operated.

Other objects will be in part obvious, and in part pointed out more in detail hereinafter.

The invention accordingly consists in the features of construction, combination of elements and arrangement of parts which will be exemplified in the construction herein-after set forth and the scope of the application of which will be indicated in the appended claims.

In the accompanying drawing, wherein I have shown, for illustrative purposes, one of the embodiments which the present invention may take,

Fig. 1 is a side elevational view of my improved trace mechanism;

Fig. 2 is an enlarged view of that end of the trace bar which carries the actuators associated with the pedal stop actions;

Fig. 3 is a top plan view of what is shown in Fig. 2; and

Fig. 4 is a sectional view taken substantially on line 4-4 of Fig. 2.

Referring to the drawing in detail, 10 designates the skeleton rollers of one set of stop action operating devices which, for convenience in description, may be assumed are 85 associated with the swell organ, or any one of the manual sub-organs. 11 designates the skeleton rollers of another set of stop action operating devices which, for convenience, may be assumed as being associated with the 90 pedal organ. The skeleton rollers 10 are adapted to be individually oscillated about their axes by suitable stop keys or pellets convenient to the hands of the organist, and these rollers may be operatively connected 95 to the several registers of pipes of which the manual is made up, the manipulative means and connections not being illustrated, as they may be of any suitable construction. In this connection, reference may be had to my said 100

Patent No. 1,079,078. The rollers 11 are operatively connected to the several registers of pipes of which the pedal organ or sub-organ is made up, and these rollers may be individually oscillated about their axes by suitable foot or hand pistons, which are not shown, as such arrangements are old and well known in the art. It is, of course, understood that the two sets of suitable actions represented by the rollers 10 and 11 may be associated with any of the sub-organs of which the general organ is made up.

Extending through the rollers 10 and 11 is a trace bar 12 on one end of which are mounted the usual actuators or cams 13 for the several rollers 10, there being a cam 13 for each roller 10. These cams or actuators, in the present illustrative disclosure, are shown as being similar in construction and operation to the actuators disclosed in my said Patent No. 1,079,078. Each comprises a T-shaped resilient member pivoted on a stud 14 projecting laterally from the trace bar 12 and having a rounded head 15. Each actuator has a pair of bosses 16 which provide concavities adapted to selectively receive the rounded head 15 of that stud which succeeds the one on which the particular actuator is pivoted. Thus, each of these actuators is settable into two separate positions, in one of which the upper arm extends above the upper end of the trace and the lower concavity receives the stud, and in the other of which the lower arm extends below the trace and the upper concavity receives the stud. These actuators are placed under tension or sprung so that they are effective at all times in each of the set positions.

Also pivotally carried by the main trace bar 12 is a plurality of actuators or cams 17 which are respectively associated with the stop actions of the pedal organ; that is to say, with the rollers 11. These actuators or cams 17 are similar in construction to the cams 13 but are mounted in a somewhat different manner in order that they may be rendered effective and ineffective at will. In the present instance, these actuators 17 are loosely pivoted on studs 14 and have bosses 19 similar to the bosses 16 of the actuators 13. As stated, these actuators are loosely pivoted; that is to say, they are not resiliently held in such manner that they retain their positions with respect to the studs in the absence of other means for holding them in those positions.

For the purpose of holding the actuators 17 in set positions there is provided a locking device which is here shown in the form of a secondary bar 25 provided with a plurality of spring elements adapted, when the bar is in operative position, to engage the actuators 17, and when in inoperative position to leave those actuators free. In the present instance, this secondary bar 25 is

located along the side of and parallel to that portion of the main trace which is provided with the actuators 17, the actuators being located between that trace and the bar 25. The bar may be supported for 70 slidable movement in any suitable manner as, for example, by means of rivets 26 projecting laterally from the main trace and having heads 27. The spring elements on the secondary or locking bar 25 may take 75 various forms. Each is here shown as comprising a U-shaped spring member 28, the free or inner arm 29 of which is adapted to engage the bosses 19 when the locking bar is in the operative position shown by dotted lines in Figs. 2 and 3. The longer arms of the spring members extend downwardly along the outer face of the locking bar, and have T-heads 30 at their upper ends. These outer arms extend through pressed 80 out bridge portions 31 on the locking bar, and the heads rest upon these bridge portions. The outer arms of the spring members are bowed, as at 32, so as to give added 85 resiliency to these members. 90

The secondary or locking bar 25 has an operative position, shown by dotted lines in Fig. 3, and an inoperative position, shown by full lines in that figure. In order to move this bar from one position to another, any suitable arrangement may be provided such, for example, as a roller 35 associated with a lever cam 36 which forms a connection between the main trace and the locking bar. The roller 35 may be similar to the other 100 rollers, and is adapted to be operated by its own individual key or tablet. The lever cam 36 is pivoted to a stud 37, and has a pair of bosses 38 adapted to selectively receive the head of the first pin 18. The body portion of this cam is normally flexed so that the cam of itself has sufficient resiliency to hold it in either of its set positions. The cam has arms 39 adapted to cooperate 105 with the respective arms of the roller 35. It also has a connecting portion or finger 40 which terminates in a hook 41 adapted to engage a notch 42 in the upper edge of, and adjacent the forward end of, the locking bar 25. 110

The operation of my improved arrangement is briefly as follows: Assuming that the organist wishes to dissociate the pedal organ stop actions from the control of the traces in order that the various registers of pipes of the pedal organ will not be interfered with or disturbed by the trace when the latter is operated, the locking bar is brought to the inoperative position shown by 120 full lines in Fig. 3 and in which position the spring elements 28 do not engage the actuators 17; therefore, these actuators are free to move or flop so that, when the trace is moved, these actuators do not disturb the positions of the rollers 11. Assuming 125 130

now that an organist desires that the pedal stop actions be under the control of the trace, he can readily change the organ from one system to another by merely operating the 5 manipulative device associated with the roller 35 so as to throw that roller to its other position, thereby depressing the cam 36 and causing the connecting portion 40 to move the locking bar to the left, that is 10 to the dotted line position shown in Fig. 3. When this is done, the spring fingers 29 are engaged with the bosses 19 and thus resiliently hold the actuators 17 in their set positions. The resistance of these actuators 15 against movement is now greater than the resistance of the rollers 11 against movement so that, when the trace is moved as a whole, these rollers will be set in accordance with the set positions of the actuators 17. 20 The actuators 17 are settable when the locking bar 25 is in the position where spring fingers 29 engage with the bosses 19. If it is desired to throw the pedal stop actions 25 readily be done by moving the roller 35 back to the position shown in Fig. 2, thereby rendering the actuators 17 ineffective when the trace is moved.

As many changes could be made in the 30 above construction and many apparently widely different embodiments of this invention could be made without departing from the scope thereof, it is intended that all matter contained in the above description 35 or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

45 I claim as my invention:

1. In a musical instrument, a set of stop action operating devices, a second set of stop action operating devices, a trace, actuators on said trace for said first set of devices and settable into two positions, and actuators on said trace respectively associated with the devices of the second set, said second mentioned actuators being renderable effective and ineffective at will, said 55 second mentioned actuators being settable like the first set.

2. In a musical instrument, a set of stop action operating devices, a second set of stop action operating devices, a longitudinally movable trace, actuators on said trace respectively associated with the devices of the first set and settable into two positions and in each of which said actuators are effective at all times, a second set of actuators 60 on said trace respectively associated with

the stop action operating devices of the second set, each of the last mentioned actuators being normally ineffective to operate the associated devices when the trace is moved, and means for rendering said actuators effective, each of said second mentioned actuators being settable into two positions when said means is in effective position. 70

3. In a musical instrument, a set of stop action operating devices, a second set of stop action operating devices, a trace, a first set of actuators on said trace respectively associated with the operating devices of the first set, a second set of actuators on the trace respectively associated with the operating devices of the second set, said last mentioned actuators being normally ineffective when the trace is moved, and means for simultaneously rendering said second set of actuators effective, said second mentioned actuators being settable when rendered effective by said means. 75 80 85

4. In a musical instrument, a set of stop action operating devices, a second set of stop action operating devices, a trace associated with both of said sets, a plurality of actuators on said trace respectively associated with the operating devices of the first set and each settable into two positions, a second set of actuators on said trace respectively associated with the operating devices of the second set and each settable into two positions, said second set of actuators being normally loose on the trace so as to be ineffective when the trace is moved, and means common to all of said second mentioned actuators for resiliently holding the same in set positions to thereby render them effective, said second mentioned actuators being settable when rendered effective by 90 95 100 105 said means.

5. In a musical instrument, a set of stop action operating devices, a second set of stop action operating devices, a trace, actuators on said trace respectively associated with the operating devices of the first set, each of said actuators being settable into two positions and being effective in each of said positions, a second set of actuators on said trace respectively associated with the operating devices of the second set, means engageable with and disengageable from said second set of actuators, said second set of actuators being loose when said means is disengaged therefrom and being held in set 110 115 120 positions when said means engages the same, and a manipulative device for moving said means into and out of engaging positions, said second mentioned actuators being settable when said means is in engaging position. 125

6. In a musical instrument, a trace, a first set of actuators on said trace and each settable into two positions and each effective at all times in its set position, a second set 130

of actuators on said trace, said second mentioned actuators being normally ineffective, and means for rendering said second mentioned actuators effective and ineffective 5 at will, said second mentioned actuators being settable in two positions when rendered effective by said means.

7. In a musical instrument, a trace, a first set of actuators thereon each settable into 10 two positions and each being effective in each of its set positions, a second set of actuators carried by said trace and each settable into two positions, means common to said second set of actuators and movable 15 into and out of engagement therewith, said means, when in operative position, being adapted to resiliently hold said second mentioned actuators in set positions, said second mentioned actuators being ineffective 20 when said means is in non-engaging position, and a manipulative device for moving said means into and out of operative position.

8. In a musical instrument, a trace, a 25 first set of actuators thereon each settable into two positions, a second set of actuators on said trace each settable into two positions, said second set of actuators being loose so that they are normally ineffective, 30 and a member movable with said trace when the latter is moved, said member being mounted for movement relative to said trace into and out of locking position, said member having means adapted to resiliently 35 hold said second mentioned actuators in set position when the member is in operative position, said means being disengaged from said actuators when said member is in inoperative position.

40 9. In a musical instrument, a trace, a first set of actuators thereon each settable into two positions, a second set of actuators loosely mounted on said trace and settable into two positions, a member carried by said 45 trace so as to move therewith when the trace is operated, said member being movable lengthwise of the trace into an operative position and an inoperative position, said member having resilient means engageable with said second mentioned actuators 50 to render the same effective and settable when said member is in operative position, said second set of actuators being ineffective when said member is in inoperative position, and a manipulative device for moving said member into and out of operative positions.

55 10. In a musical instrument, a trace, a first set of actuators carried thereby and 60 each settable into two positions, a second set of actuators loosely mounted on said trace and settable into two positions, a bar extending longitudinally of said trace and carried thereby so as to move therewith, said 65 bar being movable longitudinally relative

to the trace into and out of operative position, spring members carried by said bar and adapted to engage the respective actuators of the second set to render the same effective and settable when said bar is in operative position, said spring members being disengaged from said second mentioned actuators when the bar is in inoperative position, and manipulative means for moving said bar into and out of operative positions. 70 75

11. In a musical instrument, a trace, a first set of actuators carried thereby and settable into two positions, a second set of actuators loosely mounted on said trace 80 and settable into two positions, a bar located along the side of said trace and movable therewith when the trace is moved, said bar being movable relative to said trace into and out of operative position, spring 85 fingers carried by said bar and adapted to respectively engage said second mentioned actuators when said bar is in operative position to thereby render said actuators effective and settable, said fingers being disengaged from said actuators when the bar is in inoperative position, a lever cam between 90 said trace and bar and settable into two positions, and means including a roller for moving said lever from one position to another and thereby move said bar into and 95 out of operative position.

12. In a musical instrument, a trace, a plurality of actuators carried thereby and each settable into two positions, a second set 100 of actuators loosely pivoted to said trace and each settable into two positions, a locking bar, means on said trace for supporting said locking bar for longitudinal movement into and out of operative position, resilient 105 means carried by said locking bar and adapted to engage said second mentioned actuators when the bar is in operative position so as to render said actuators effective and settable, said resilient means being disengaged from said actuators when said locking bar is in inoperative position, a lever cam pivoted to said trace and operatively connected to said bar, said lever cam being 110 settable into two position in one of which said bar is held in inoperative position and in the other of which said bar is held in operative position, and a manipulative device 115 including a roller for moving said lever cam from one position to another.

13. In a musical instrument, a trace, a first set of actuators pivoted thereto and settable into two positions, a second set of actuators loosely carried by said trace and each settable into two positions, rivets carried by said trace, a locking bar supported by said rivets for longitudinal movement into and out of operative position, U-shaped 125 spring members carried by said bar, said members having free arms adapted to re- 130

spectively engage said second mentioned actuators when said bar is in operative position and being disengaged from said actuators when said bar is in inoperative position, and means for moving said bar into and out of operative position.
